UNITED STATES PATENT OFFICE.

HENRY SPENGLER, OF NEW YORK, N. Y., ASSIGNOR TO ALFRED LIEBMANN, OF BROOKLYN, NEW YORK.

CLOSURE.

1,074,907.

Specification of Letters Patent. Patented Oct. 7, 1913.

Application filed June 5, 1911, Serial No. 631,267. Renewed June 22, 1912. Serial No. 705,812.

To all whom it may concern:

Be it known that I, HENRY SPENGLER, residing at New York, in the county and State of New York, have invented certain new and useful Improvements in Closures, of which the following is a specification.

This invention relates to caps or closures, particularly adapted for use as bottle closures, though their use is not limited to this relation.

One of the objects of the invention is to produce a device of the kind referred to which is readily put into place, which effectually accomplishes its sealing or covering function, and which may be removed without the use of any tools whatsoever.

The invention provides a bottle cap having a central resilient portion normally bulged to one side of a plane and yieldable under pressure, said cap having means gripped to the bottle mouth while the normal bulge is maintained and released therefrom when the bulged portion is depressed, and said bulged portion adapted to spring away from said releasing position of its own resiliency.

In the accompanying drawings which are to be taken as a part of this specification, in which I have shown a merely preferred form of embodiment of the invention; Figure 1 is a view of the mouth portion of a bottle as an example of a member to which my invention is applicable, showing an embodiment of the invention in place as it will appear when the bottle is sealed by it; Fig. 2 is a central sectional view of the subject matter of Fig. 1 with the bottle partly in elevation; Fig. 3 is a plan view of one of the closure members which may be employed in connection with my invention; Fig. 4 is a view similar to Fig. 2, but showing the relation of the parts when the closure device has been manipulated to enable it to be released from the bottle; and Fig. 5 is a central sectional view of the mouth part of a bottle provided with a modified form of embodiment of the invention.

Referring to the numerals on the drawings, 1 indicates the mouth part of a bottle, which is preferably flanged as indicated at 2. The construction may be of the kind now generally used in connection with what are known as crown seals. A sealing disk 3 of cork or other suitable material overlies

the mouth of the bottle substantially as shown in Figs. 2, 4, and 5, as is the case with the ordinary crown seal, and this disk 3 is held with its peripheral portions compressed against the edges of the bottle 60 mouth by means of the closure member now to be described. This closure member comprises preferably a disk of resilient metal as shown in Fig. 2, having a permanent set causing it to bulge slightly in the center, 65 as indicated at 4, and having peripheral fingers 5 which may be defined by slits 6 cut in the periphery of the disk and extending radially or at least in the general direction of the center of the disk. Such a 70 device as is shown in Fig. 2 is placed over the mouth of a bottle, with a sealing disk 3 interposed between it and the mouth of the bottle as shown in Figs. 2, 4 and 5, and the peripheral fingers 5 bent downwardly 75 by any appropriate means so that they will engage over and beneath the flange 2 of the bottle with such force as may be necessary to tightly seal the bottle, this operation being substantially similar to that 80 which takes place in applying the ordinary crown seal. When the parts are thus in place as shown in Fig. 2, the central part of the disk will be dished outwardly as shown in said figure, and the fingers 5 will be bent abruptly 85 downward from said central portion; it being understood that the slits 6 which define said fingers should preferably be of such length that they will not extend inwardly beyond the bend of the fingers. If 90 now pressure be applied centrally of the dished portion of the disk so as to spring the same into the position of Fig. 4 (which position it will hold until forced reversely), the leverage thus exerted on the fingers 5 95 will tend to spread the same away from the flange of the bottle, whereupon the closure may be readily removed. It is contemplated that this operation should be done by hand, the pressure of the thumb 100 upon the bulge of the disk being ordinarily sufficient where metal of the proper thickness and resiliency is employed in the making of the disk; and the device may be sealed the second time, by springing the 105 bulge back to its first position as shown in Fig. 2, and then forcing the contracted fingers over the bottle flange. Of course, in the case of such second use the grip would not be so strong as when the device 110

is put on the first time, and the bottle might not be absolutely sealed. But in any event the device will serve in such second use as a cover. In case a person should 5 not be able to release the closure by thumb pressure, it will only be necessary to press the bulge against the corner of a table or the like.

I may provide a metallic closure made 10 with its central portion more resilient than its portions adjacent the inner ends of the fingers 5. This may be accomplished by thinning the central portion of the disk as indicated at 9 in Fig. 3, as by stamping or 15 beating the said central portion of the disk and thereby thinning it. Ordinarily I prefer that in the course of this thinning operation the said central part shall be slightly outwardly bulged. With this structure the bulge of the closure need not be very 20 pronounced, and yet the device will be effective for the purposes of the invention.

Referring to Fig. 5 I show an embodiment 25 of the invention wherein the bulge of the disk is protected so that the device is not apt to be released accidentally. In this embodiment I provide a bulge as before, and the periphery of the bulge is defined by an upwardly extending flange 7, from which extend the fingers 5 as in the embodiment here- 30 tofore described. Thus the fulcrum for the leverage exerted upon each finger 5 by the operation of the bulge is in the line of junction between the bulge and the upwardly 35 extending part or flange 7, while the bulge is entirely below the plane of the inner ends of said fingers 5, so that the bulge can be operated only by pressure exerted in a directly downward direction. When the device 40 of Fig. 5 is placed in position and the fingers 5 bent downwardly as shown, and under the flange 2 of the bottle, the sealing disk 3 will be compressed adjacent its peripheral edge between the mouth of the bottle and the edge 45 of the bulge. If desired I may provide also an annulus 8, centrally cut out, and tapering in thickness from the center toward the edges. The object of this annulus is to provide a substantially flat top for the closure. 50 With respect to the forms of the invention thus described, it will be apparent that they may be embellished in the usual way by means of lithography or the like, preferably applied upon the central dished portion before the disk is bent into shape about the mouth of the bottle. Furthermore the disk 55 may be stamped into shape, with bulge and fingers, at trifling expense; and the application of the disk to a bottle may be accomplished by automatic machinery as is done with the ordinary crown seal.

I have described the invention as embodied in a bottle closure, but it is to be understood that I do not mean to limit it for 60 use in connection with bottles of the type

indicated, but have in mind its use as a closure for containers of any description. Neither is it necessary that the disk should be circular; it might be of some other outline.

As many changes could be made in the above construction and many apparently widely different embodiments of this invention could be made without departing from the scope thereof, it is intended that all matter contained in the above description or 75 shown in the accompanying drawing shall be interpreted as illustrative and not in a limiting sense. It is also to be understood that the language used in the following 80 claims is intended to cover all of the generic and specific features of the invention herein described and all statements of the scope of the invention, which as a matter of language, might be said to fall therebetween.

Having thus described my invention, what 85 I claim as new and desire to secure by Letters Patent is:

1. A bottle closing cap comprising a resili- 90 ent disk having a central bulged portion capable of being sprung into two reverse positions, the bulge being on one side of a plane when one of the two positions is assumed, and on the other side of the plane when the other position is assumed, and fingers integral with said central portion and depending from the periphery thereof at one side of said central portion in circular arrangement, said fingers being separated from each other, the free ends of said fingers, when the bulge is sprung away from the fingers, moving toward the center of the circle on which they are arranged, and, when the bulge is sprung into its second position or toward the fingers, moving away 105 from the center of said circle.

2. A bottle closing cap comprising a resili- 110 ent disk having a central bulged portion capable of being sprung into two reverse positions, the bulge being on one side of a plane when one of the two positions is assumed, and on the other side of the plane when the other position is assumed, and fingers integral with said central portion and depending from the periphery thereof at 115 one side of said central portion in circular arrangement, said fingers being separated from each other, the free ends of said fingers, when the bulge is sprung away from the fingers, moving toward the center of the circle on which they are arranged, and, when the bulge is sprung into its second position or toward the fingers, moving away 120 from the center of said circle, there being an upstanding peripheral flange on that side 125 of the disk away from the fingers, the edges of said flange being in a plane beyond that of the bulge when the latter is sprung into position away from the fingers.

3. A cap for bottles or the like having a 130

central portion and separated fingers depending therefrom and integral therewith, said central portion having a permanent set causing it to bulge outward when said fingers are in gripping position, said fingers being movable from the gripping position by pressing the bulge inward, the material of the cap being resilient so that the central portion tends to spring to its outward bulged position when brought approximately thereto, whereby the cap is capable of reuse after being used and released.

4. A cap for bottles or the like consisting of a single piece of sheet metal having a central portion and a series of fingers, said separate fingers being integrally connected with the central portion, and normally adapted to occupy inward or clamping positions to engage the bottle mouth, and said central portion having a permanent set

causing it to bulge to one side of the plane of its connection with the fingers, and adapted to spring said fingers outwardly away from their clamping positions when the central portion is moved in the direction 25 of said plane, and said central portion being resilient and capable of springing from said plane to an extreme position away from said plane, and said fingers being connected to said central portion and being adapted to 30 spring toward their inward or clamping positions when the central portion springs to its outermost position.

In testimony whereof I have affixed my signature in the presence of two witnesses. 35

HENRY SPENGLER.
